UNITED STATES PATENT OFFICE

163,853

RELIGIOUS ILLUSION PLAQUE

Enrico Cerracchio, Brooklyn, N. Y.

Application April 26, 1950, Serial No. 9,483

Term of patent 14 years

(Cl. D29—23)

To all whom it may concern:

Be it known that I, Enrico Cerracchio, a citizen of the United States of America, residing in Brooklyn, in the county of Kings and State of New York, have invented a new, original and ornamental Design for a Religious Illusion Plaque, of which the following is a specification, reference being had to the accompanying drawing, forming part thereof.

Fig. 1 is a front elevational view of a religious illusion plaque, showing my new design;

Fig. 2 is a side elevational view of the design shown in Fig. 1;

Fig. 3 is a rear elevational view of the design shown in Fig. 1;

Fig. 4 is a horizontal sectional view taken on the line 4—4 of Fig. 1 looking in the direction of the arrows;

Fig. 5 is a vertical sectional view taken on the line 5—5 of Fig. 1;

Fig. 6 is a perspective view from the right of the article shown in Fig. 1; and

Fig. 7 is a perspective view from the left of the article shown in Fig. 1.

I claim:

The ornamental design for a religious illusion plaque, substantially as shown.

ENRICO CERRACCHIO.
